UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER LOOM.

Application filed September 22, 1921. Serial No. 502,526.

To all whom it may concern:

Be it known that I, JONAS NORTHRUP, a citizen of the United States, residing at Hopedale, in the county of Worcester and 5 State of Massachusetts, have invented certain new and useful Improvements in Feeler Looms; and I do hereby declare the following to be a full, clear, and exact description of the invention, such as will enable others 10 skilled in the art to which it appertains to make and use the same.

The present invention relates to an improvement in feeler looms, and more particularly to feeler looms of the box type.

15 The application of feeler controlled weft replenishing mechanism to box looms is attended by a complication incident to the fact that the boxes are rising or falling at the time the feeling operation is performed. 20 The inactive shuttle is moving from inactive to active position at the time the feeler is operating to determine the critical exhaustion of the filling.

According to the present invention it is 25 proposed to provide the loom with a plurality of feelers, one for each box, and to raise and lower the feelers with the boxes so that each feeler maintains a correct vertical position with relation to its box at all 30 times, and in addition to connect the feeler with the change mechanism for throwing the weft replenishing mechanism into operation at the time when it is feeling the bobbin in the shuttle which is about to become the active shuttle.

35 The object of the invention is to produce an improved weft replenishing loom of the box type provided with filling feeler mechanism, and the invention consists in the construction hereinafter described and particularly defined in the claims.

In the accompanying drawings illustrating 40 the preferred form of the invention as embodied in a box loom having two boxes, Fig. 1 is an end elevation of a loom with the shuttle boxes shown in section; Fig. 2 is a front elevation of the feelers and a portion of the connections between them and the change mechanism controlling the weft 45 replenishing mechanism; Fig. 3 shows parts illustrated in Fig. 2 with one of the feelers in feeling position; Fig. 4 is an end view of the construction illustrated in Fig. 3; Fig. 5 is a plan view of the lay, the feeler

and change mechanism; and Fig. 6 is a 55 side elevation of the change mechanism.

The illustrated embodiment of the invention is described as follows:

The loom frame 1, the crank shaft 2, the lay 3, the cam shaft 4, the shuttle boxes 5 and 6, are or may be constructed as is usual in box looms. The boxes are raised and lowered by the rods 8, on the upper end of which they are carried, which slide vertically on the lay structure, being raised and lowered by the link 9, connected at its lower end to the slide 10, which carries the rods 8, and at its upper end to the rocking beam 11, pivoted at 12 to the frame of the machine, which rocking beam is oscillated by the pitman 13 connected at its upper end to the rocking beam 11, and at its lower end to the crank 14 which is operated by the Geneva motion from the cam shaft 4. The shuttles 20 and 21 are carried in the boxes 5 and 6, respectively, and associated with each shuttle is a feeler, the feeler 22 being 60 associated with the shuttle 20, and a feeler 23 being associated with the shuttle 21. These feelers are mounted on a bracket 24, bolted on the slide 25, which is reciprocated in the bearing 26 by means of a pitman 27, connected at its upper end with the slide 25, and at its lower end to the box slide 10, mounted on the lay structure. It is apparent, therefore, that as the boxes are 65 raised and lowered to move one or the other shuttle to active position, the feelers are likewise raised and lowered at the same time.

The particular feeler mechanism is that illustrated in Patent No. 1,249,280, granted to me December 4, 1917. The feeler has a filling engaging member 30, mounted on the end of a feeler lever 31, being pressed rearwardly in a direction to engage the filling 70 on the bobbin by a spring 29, which yields when the filling engaging member comes in contact with the filling. The feeler lever 31 is pivotally mounted on the stud 32, supported in a bracket 24, and a spring 33, surrounding the hub of the feeler lever, normally tends to turn the feeler lever in a direction to cause the filling engaging member to move away from the butt of the bobbin. This spring 33 is a light spring, 75 and it exerts only sufficient force upon the feeler lever to hold it lightly against the surface 34 of the bracket upright 35, which

2
is a support for the upper end of the feeler lever actuator 36. The upright 35 is supported at its lower end in the bracket 37, to which the lower end of the feeler lever actuator 36 is pivotally attached at 38. The feelers are raised and lowered in timed cooperation with the raising and lowering of the boxes, and each feeler normally occupies the position indicated in Fig. 5, with the 10 rear end of the feeler lever in engagement with the surface 34 of the upright 35, by reason of the light pressure exerted upon the feeler levers by the spring 33. As the feelers are raised and lowered, they pass 15 by projections 40 and 41 on the side of the feeler actuator 36. Thus, as the upper feeler is lowered into active position, the rear end of its feeler lever passes the operating surface of the projection 40 as the lay moves 20 forward, and the feeling movement of the feeler is imparted to it by the contact of the projection 40 of the rear end of the feeler lever as it passes by it.

In the construction illustrated in said 25 patent, the feeler lever was held in normal position by the link which connected it with the latch lever. In the present construction the feeler levers 31 are held in normal position by the spring 33, and at 30 the time of feeling, the feelers are passing the one or the other of the projections 40 and 41 on the feeler lever actuator 36. This feeler lever actuator 36 is connected by means of a link 39 with the latch lever 35 35 42, which is pivoted on a pin 43 on the controller slide 50. A spring 45 presses against the latch lever 42, and normally tends to move it in a direction to exert a pull upon the link 39 so as thereby to tend 40 to move the feeler actuator 36 to the right, as viewed in Fig. 2, and this is permitted by the controller 44 to occur at the time the feeler lever is passing either the one or the other of the projections 40 and 41 on 45 the feeler actuator 36. The spring 45 is a stronger spring than the spring 33, being of sufficient strength to move the actuator against the resistance of the spring 33, so as to tend to turn the feeler anti-clockwise, as viewed in Fig. 5, which tendency 50 will be sufficient to turn the feeler in that direction when critical exhaustion of filling on the bobbin has been reached; that is to say, when the filling on the bobbin 55 no longer is sufficient to hold the feeler from being turned by the means described.

In the construction of said patent, the connection between the latch lever and the feeler is continuous. In the construction 60 herein described the connection between the latch lever and the feeler is discontinuous, the latch lever tending to turn the feeler at the time when the feeler lever is passing a projection on the feeler actuator.

65 The controller 44 is mounted on the con-

troller slide 50, which is pivotally connected at 51 with the change lever 52, mounted on the change shaft 53, connected in the usual manner with the weft replenishing mechanism. The controller slide 50 70 is provided at its rear end with a foot 54, which is received in a slideway 55, secured to the breast beam 56. The spring 45 which tends to turn the latch lever 42, as above described, presses at one end against a portion of the latch lever on the opposite side of its pivot from that at which the link 39 is attached, and it presses at the other end against an abutment screw 57, which is cupped to receive it and screwthreaded 75 through a hole in the controller slide 50 and secured in adjusted position by the nut 58. The controller slide is provided with two ears 60, which support the pin 43, constituting the pivot upon which the latch 80 lever 42 is pivoted.

The latch lever is provided with a pin 46 which projects up from its body and is adapted to be engaged by a lug 47, which projects laterally from the side of the controller 44. This lug 47 is normally held in rearward position, by means presently to be described, in engagement with the pin 46, thereby holding the latch lever in the position illustrated in Fig. 5, that is, in its inactive position. In the condition of the parts illustrated in Fig. 5, the latch lever has been released by the controller, the feeler has come into engagement with a bobbin, and the spring 45 is normally tending 90 to turn the latch lever in a direction to exert a pull upon the link 39 so as thereby to move the feeler actuator to cause the feeler to move toward the bobbin butt, such movement, however, is resisted and prevented 95 by the yarn on the bobbin. The controller 44 is also provided with a vertical projection 61 on the side opposite from the lug 47, which projects into an opening 62 in the enlargement on top of the controller 100 slide 50. A spring 64 received in a spring cavity in the enlargement 63 presses against the upper end of the projection 61. From the lower end of the projection 61 there extends the lug 65, which projects out 105 through the horizontal slot 66 in the side of the enlargement 63. A washer 67 encircles this projection 65, and a cotter pin 68 is employed to hold the controller on the controller slide. The forward end of the controller slide is provided with a support 70, which has a portion which engages the under side of the controller and a portion which engages the side of the controller, as shown. The above described construction 110 is such that the controller is slidingly and pivotally mounted on the controller slide, the slot 66 permitting the controller to move forwardly and backwardly with relation to the controller slide, and the projection 65 115 120 125 130

which passes through the elongated hole 66 permits the controller to tip on the projection 65 as a pivot, the spring 64 performing the double function of tending to hold 5 the controller in its rearward position, and as well in its depressed position. The under surface of the rear end of the controller is curved, as shown, and is adapted to be engaged by the upper end of the weft hammer 80. When the weft hammer is in its forward position, it engages and lifts the controller so that the controller stud 71, mounted in the end of the controller 44, is lifted above the bunter 81, mounted on 10 the lay. The controller stud 71 is adjustable in the controller by being screw threaded through the end of the latter, and it is secured in adjusted position by a set nut. On the beat of the lay when the 15 active shuttle is boxed at the feeler end of the lay, the weft hammer occupies a rearward position, and thus permits the controller to occupy its depressed position with the stud 71 in the path of motion of the 20 bunter 81. When, however, the active shuttle occupies the box on the opposite side of the loom, the weft hammer in its forward movement lifts the controller so as to raise the controller stud 71 above the 25 bunter 81 on the lay, so that on this beat of the lay there is no feeling operation performed.

The operation of the loom is as follows: As is usual in box looms of this type, the 30 active shuttle is picked from the feeler side of the loom to the replenishing side of the loom, and then picked back again. Then the shuttle boxes are moved to bring the other shuttle to active position, and it is 35 picked across the loom and back again. The filling feelers are located opposite each shuttle box, being raised and lowered in synchronism therewith. Each filling feeler is normally held in position to engage the filling 40 on the bobbin opposite it on each beat of the lay. The feelers are normally held from turning, but as a shuttle moves from inactive to active position during a forward beat of the lay, the forward end of the particular feeler which engages the bobbin on 45 such shuttle is passing the projections 40 or 41 of the feeler actuator, and at this time such feeler actuator is pulled upon by the latch lever through the link 39, as at this 50 time the controller is moved forward sufficiently to relieve the pressure of the lug 47 on the pin 46 of the latch lever, so that the spring 45, through the latch lever link and feeler actuator, tends to turn the feeler anti-clockwise, and will do so unless the yarn on 55 the bobbin prevents. When critical exhaustion of the filling has been reached, the feeler will turn under the influence of the connections described, and thus permit the 60 latch lever to turn and bring its weft ham-

mer engaging face 90 in front of the knife 91 of the weft hammer 80, whereupon the weft hammer will force the latch lever forwardly, carrying with it the controller slide 67 operating the change shaft 53 to effect 70 replenishment of the shuttle, critical exhaustion of the bobbin of which has been indicated.

It will be observed that the feeler illustrated herein performs its feeling operation 75 during the forward movement of the lay, and while the boxes are being changed; also that while there is provided a feeler for each shuttle, and while the feeler is located at all times in proper position to enter the 80 shuttle and feel of the bobbin, it only operates to indicate critical exhaustion during the forward movement of the lay, the vertical movement of the feeler bringing it opposite the active surface of the feeler 85 actuator, so that the connection between the change mechanism and the feeler is not only discontinuous, but caused to occur at the time a shuttle is moving from inactive to active position. It is also to be observed 90 that features of construction of the controller and feeler are adapted for use on constructions of looms of other types than box looms.

Having thus described the invention, what 95 is claimed is:

1. A box loom having, in combination, a lay, a plurality of change boxes on one end of the lay, weft replenishing mechanism, a plurality of feelers, one for each change 100 box, means for actuating the change boxes and feelers to raise and lower them simultaneously, a controller mechanism comprising a controller and connections between it and the weft replenishing mechanism, and 105 connections between the controller and the feelers having provision by virtue of which the feeler entering the shuttle moving into active position is connected with the change mechanism.

2. A box loom having, in combination, a lay, a plurality of change boxes on one end of the lay, a plurality of feelers mounted on the loom, means for moving the change boxes and feelers so as to maintain the same 110 relation of the feelers with the boxes at all times, a feeler actuator for actuating the feeler to make its feeling movement, weft replenishing mechanism, a controller, connections between the controller and feeler actuator having provisions for moving the feeler actuator to cause a movement of the feeler corresponding to the shuttle moving into active position, connections between the controller and weft replenishing mechanism 115 for causing the operation of the latter upon critical exhaustion of the filling in the shuttle moving into active position.

3. A box loom having, in combination, a lay, a plurality of boxes mounted on one end 120

of the lay, weft replenishing mechanism, a plurality of feelers mounted on the loom, means for actuating the change boxes and feelers to maintain each feeler in cooperative position with relation to its shuttle box, a feeler actuator having portions adapted to cooperate with each feeler and to actuate such feeler when it is moving into active position with its shuttle, and connection between the feeler actuator and the weft replenishing mechanism.

4. A box loom having, in combination, a lay, two change boxes on the lay, means for raising and lowering the change boxes to bring first one and then the other of the shuttles into active position, a feeler for each shuttle box, a slide on which the feelers are mounted, connections between the slide and the means for raising and lowering the shuttle boxes, in timed cooperation with the shuttle boxes, a feeler actuator mounted on a stationary part of the loom provided with two surfaces, the one for engagement with one feeler, the other for engagement with the other feeler, each surface engaging the feeler corresponding to the shuttle coming into active position, weft replenishing mechanism, and connections between the weft replenishing mechanism and the feeler actuator having provision for actuating the feeler corresponding to the shuttle coming into active position upon critical exhaustion of the filling therein.

5. A feeler loom having, in combination, a lay, a shuttle box, a feeler, means for normally holding the feeler in feeling position, weft replenishing mechanism, a controller, connections between the controller and the weft replenishing mechanism, discontinuous connections between the controller and the feeler having provision for actuating the feeler to make its feeling movements as the lay beats forward.

6. A feeler loom having, in combination, a lay, a feeler, weft replenishing mechanism, a controller, a weft hammer, a latch lever adapted to be moved into the path of the weft hammer to initiate weft replenishment, and discontinuous connections between the latch lever and the feeler having provision for making the connection between the latch lever and the feeler to impart a feeling movement to the feeler as the lay moves forward on a detecting beat, and to permit movement of the latch lever into the path of the weft hammer in the absence of filling.

7. A feeler loom having, in combination, a lay, a feeler, weft replenishing mechanism,

a controller slide, a controller mounted on the slide, connections between the latch lever and the feeler, said controller being pivotally and slidably mounted on the controller slide and provided with means normally acting to hold the latch lever in inoperative position, a bunter on the lay for actuating the controller to release the latch lever, and a weft hammer for actuating the latch lever and controller slide upon critical exhaustion of the filling to cause weft replenishment.

8. A feeler loom having, in combination, a lay, a feeler, weft replenishing mechanism, a controller slide, connections between the controller slide and the weft replenishing mechanism, a latch lever pivotally mounted on the controller slide, a weft hammer, a controller normally holding the latch lever in inoperative position, a bunter mounted on the lay, connections between the feeler and the latch lever, said controller being slidably and pivotally mounted on the controller slide adapted to be lifted by the weft hammer out of the path of motion of the bunter on non-detecting beats of the lay, and to be permitted on detecting beats of the lay to occupy its normal position in the path of motion of the bunter, and a spring normally holding the controller in rear position on the controller slide.

9. A feeler loom having, in combination, a lay, a feeler, weft replenishing mechanism, a controller slide, connections between the controller slide and the weft replenishing mechanism, a weft hammer, a latch lever mounted on the controller slide, a controller, having a portion to engage and normally hold the latch lever in inoperative position, means for normally holding the feeler in operative position, discontinuous connections between the feeler and the latch lever, a bunter, said controller having a cam surface adapted to be engaged by the weft hammer for tilting the controller to move it out of the path of motion of the bunter.

10. A box loom having, in combination, a lay, a plurality of change boxes mounted on one end of the lay, weft replenishing mechanism, feelers for each box, a slide on which the feelers are mounted, means for actuating the change boxes and feeler slide for moving them and maintaining each feeler in cooperative position with relation to its box, and means for imparting a feeling movement to the feeler corresponding to the box which receives the shuttle next to be picked.

JONAS NORTHOP.
